CYLINDER AND PISTON AND METHOD OF
PRODUCING A WORKING SEAL THERE-
BETWEEN

Judson Williams, Philadelphia, Pa.

Application February 7, 1942, Serial No. 429,914

2 Claims. (Cl. 309—2)

This invention relates to an improved cylinder and piston and method of producing a working seal therebetween, being more particularly concerned with certain improvements and developments arising out of the practice of the invention disclosed in my copending application filed May 9, 1941, Serial No. 392,796 and bearing the same title.

Under the disclosure in my copending application above identified, the cylinder is first indented externally to provide one or more internal rings on the cylinder wall, when the piston is used to broach said rings to form a working seal with the piston. It has been discovered, however, that a working seal may be provided between the piston and cylinder without first indenting the cylinder wall.

An object of the present invention, therefore, is to provide a working seal between the piston and cylinder without the use of rings on the piston and without indenting the cylinder wall to form rings.

A further object of the invention is to provide a construction wherein the cylinder wall will be formed by the piston with an annular, burnished area to coact with the piston and provide a working seal therewith, and wherein said area will be of a width substantially equal to the stroke of the piston so that the working seal between piston and cylinder will be continuous throughout the stroke of the piston.

Another object of the invention is to provide a construction wherein the piston will be employed to first broach the cylinder wall at the sealing area to the peripheral shape of the piston so that said area will, as a result, exactly conform to the contour of the piston, and wherein subsequent reciprocation of the piston will serve to burnish the broached area and provide a highly polished surface to form a working seal with the piston.

And the invention seeks, as a still further object, to provide a construction wherein the piston will be hardened and will also be machined to provide a distinctly defined, circular shearing edge at the upper end of the piston so that the piston will adequately serve as a broach for shaping the cylinder wall to the contour of the piston.

Other and incidental objects of the invention will appear during the course of the following description, and in the drawing:

Figure 1 is a transverse vertical sectional view showing a miniature engine embodying the present improvements.

Figure 2 is an enlarged vertical section showing the cylinder before being broached.

Figure 3 is an enlarged fragmentary section showing the piston near bottom center and on the up-stroke.

Figure 4 is a view similar to Figure 3 but showing the piston further up in the cylinder.

Figure 5 is an enlarged fragmentary section showing the burnished sealing area formed by the piston.

Referring now more particularly to the drawing, it will be seen that I have shown the present improvements in conjunction with a miniature motor as used upon miniature aeroplanes, miniature motor boats and miniature automobiles as well as for miniature power units, as said improvements are especially applicable to such an engine. In describing the invention, I shall accordingly refer to an engine of the character indicated. However, I do not wish to be limited in this regard as it has been found that the improvements are equally applicable to engines of larger size, such as automobile engines, as well as other adaptations, such as the injector pumps of Diesel engines and, accordingly, all such variations are to be considered within the spirit and scope of the invention.

As the construction and operation of the engine as a whole is unnecessary to an understanding of the present invention, I have shown only such parts as are pertinent. The engine is of two-cycle design and includes a cylinder 10 and crank case 11. The crank case journals a crank shaft on the rear end of which is a disk 12 carrying a crank pin 13, and reciprocable in the cylinder is a piston 14 having a wrist pin 15 journaling a connecting rod 16 engaged with the crank pin 13. At the upper end of the cylinder is an appropriate firing chamber 17.

The cylinder 10 is preferably of a suitable aluminum alloy as is also the piston 14. Other suitable materials may be employed but it has been found important, however, that the piston and cylinder have the same coefficient of expansion. For this reason, the piston should be of the same aluminum alloy as the cylinder, or other material chosen. As will be observed, the piston is without rings but may be provided with one or more peripheral oil grooves 18. In the present instance, I have shown a groove above and a groove below the wrist pin 15.

As particularly brought out in Figure 2 of the drawing, the wall of the cylinder 10 is initially thicker toward the upper end of the cylinder so that, internally, the cylinder is more or less of

truncated cone shape. The same result may, of course, be achieved by moulding or casting or otherwise forming the cylinder with a wall of uniform thickness but tapered bore.

Formed within the cylinder 10 at its upper end is a counterbored wall-surface 19. See Figures 3, 4 and 5 of the drawing. After being fashioned with a tapered bore, the upper end portion of the cylinder is, as seen in Figures 1, 3, 4 and 5 of the drawing, then preferably machined internally to define the wall surface 19 which forms the periphery of the firing chamber 17. Thus, the wall of the firing chamber is straight so that the volume of said chamber will not be reduced by the original taper of the cylinder bore. If deemed necessary, the counterbored firing chamber may in the finished engine be slightly larger in diameter than the bore of the cylinder at the lower limit of said chamber or the chamber may be so formed as to be of the same diameter as the bore of the cylinder after being broached by the piston, as will be later explained.

At the lower end portion of the cylinder, the bore thereof may, as suggested in Figure 2, be more or less uniform to initially receive the piston 14 with a close working fit. However, at said end of the cylinder, slightly greater clearance is preferably provided between piston and cylinder than what would be considered normal or standard practice, but customary tolerances are observed. Thus, any one piston may be assembled with any one cylinder without the necessity of matching, as it has been found extremely difficult, in making pistons and cylinders of miniature engines, to fashion the parts of exactly uniform size.

As compared with the wall of the cylinder 10, the piston 14 is hardened in any preferred manner so that as the engine is broken in, the piston will effectively provide a broach for shaping said wall. The piston is of substantially uniform diameter from end to end and the peripheral surface thereof is smooth while the piston is machined so that the upper end thereof or, at least, the peripheral margin of the upper end of the piston is square with said surface. A distinctly defined, circular shearing edge 20 is thus provided at the upper end of the piston for initially broaching the cylinder wall.

It is to be understood that Figures 2, 3, 4 and 5 of the drawing have been greatly exaggerated and it is not intended that the showing shall create the impression that initial upward movement of the piston 14 in the cylinder 10 would burst the cylinder nor is the showing to be so construed. At best, the gradual upward contraction of the cylinder bore is measured only in terms of thousands of an inch. As such minute measurements may not be illustrated on the drawing, pretense in this respect has not been attempted but, rather, exaggeration employed to provide a more graphic showing.

In this connection, it should be noted that to taper the cylinder bore, as previously described, is but one way of initially forming the cylinder. If preferred, the lower end portion of the cylinder may be of one uniform internal diameter to receive the piston 14 with a close working fit, and the upper end portion of the cylinder of a slightly smaller initial, internal diameter, the junction between the two being gradually merged. As the piston is to act as a broach while the engine is being broken in, the lower end portion of the bore of the cylinder must, of course, be fashioned to a close working fit with the piston

in order that the piston may be initially installed. However, in any event, it is intended that the internal contour of the wall of the cylinder will initially be such that said wall will be broached by the piston, as the engine is broken in, for substantially the full length of the stroke of the piston.

Assuming now that the piston 14 has been initially installed in the cylinder 10 and the engine is to be broken in, it has been found that this may be accomplished by operating the engine under its own power. As the piston moves upwardly in the cylinder, the shearing edge 20 of the piston will function to broach the wall of the cylinder to the exact peripheral contour of the piston so that, after a very short time, the piston will reciprocate without broaching effect and the engine will operate freely. The period of time required to break in the engine has been found to be very short, after which the broaching effect of the piston on the cylinder wall ceases and said wall is subjected by the piston only to a burnishing action.

Figure 3 of the drawing shows the piston 14 near the beginning of its upward stroke while Figure 4 shows the piston further up in the cylinder. As will be appreciated, the piston will, as the engine is broken in, broach the cylinder wall substantially throughout the full stroke of the piston, after which the broached band will be burnished by the piston to provide, as seen in Figure 5, a highly polished, annular sealing area 21 to coact with the piston and provide a working seal therewith.

It is to be noted that since the cylinder wall is broached by the piston, the sealing area 21 will exactly conform to the contour of the piston throughout the periphery thereof so that a working seal between piston and cylinder will be provided throughout the circumference of the piston.

As is well known, such a circle-seal may not be completely gained by the use of piston rings and, moreover, since in the present instance the use of rings on the piston is eliminated, the frictional drag of such rings is avoided. Furthermore, it is to be noted that the sealing surface 21 will exert no resilient, gripping drag on the piston or, at least, no appreciable drag in any way comparable to the drag exerted by resilient rings either on the piston or on the cylinder wall. This factor has been found of great gain in a miniature engine while, also, the necessity for lapping the cylinder and piston is avoided.

Experience in the manufacture of miniature engines has shown that it is difficult to produce such small pistons exactly round and maintain low-cost production. Also, the small rings required for such a piston have been found to be expensive. However, by utilizing the piston to broach the cylinder wall, the sealing surface 21 will fit the piston even though the piston may be slightly out-of-round while, also, a more effective working seal will be had between piston and cylinder than if rings were employed on the piston.

In adapting the invention to Diesel injector pumps, however, or in other similar adaptations, it may be necessary to fashion the piston exactly round as, for certain of the pumps noted, the piston must be rotated as well as reciprocated while, also, the circle-seal between piston and cylinder must still be maintained.

Having thus described my invention, what I claim is:

1. In an internal combustion engine, the combination of a cylinder having a roughly finished

bore the lower end portion of which is of uniform diameter and the upper end portion of which is tapered toward the upper end of the cylinder, and a piston reciprocal in said cylinder to form a working part of the engine and of uniform diameter to freely fit in the lower end portion of said bore, the piston having an individual roughly finished peripheral contour untreated to match the lower end portion of the bore of the cylinder and being provided at its upper end with a hardened and finished peripheral cutting edge harder than the material of the cylinder and movable on the up-stroke of the piston to cut the wall of the cylinder at the tapered portion of the bore thereof to the exact roughly finished peripheral contour of the piston and establish a close-fitting working seal between the piston and cylinder.

2. The method of forming a working seal be-

tween a cylinder and coating piston unfinished to match each other which includes the steps of forming the bore of the cylinder straight at its lower end portion and tapered at its upper end portion toward the upper end of the cylinder, forming the piston with a roughly finished individual peripheral contour to freely fit in the straight portion of said bore, treating the piston to render the same harder than the material of the cylinder, finishing the upper end of the piston to define a hardened peripheral cutting edge, and cutting the tapered portion of the bore of said cylinder by said edge as the engine is broken in to the exact roughly finished peripheral contour of the piston and establishing a close-fitting working seal between the piston and cylinder.

JUDSON WILLIAMS.
